UNITED STATES PATENT OFFICE.

GEORGE M. EAMES, OF BRIDGEPORT, AND JOHN C. RINGE, OF STRATFORD, CONNECTICUT, ASSIGNORS TO THE SINGER MANUFACTURING COMPANY, OF ELIZABETH, NEW JERSEY, A CORPORATION OF NEW JERSEY.

HEMSTITCH-SEWING MACHINE.

Application filed March 12, 1928. Serial No. 260,835.

This invention relates to improvements in needle-vibrating mechanisms for multiple-needle hemstitching machines and has for its primary object to increase the range of use 5 of hemstitching machines employing a needle-vibrating mechanism which is durable at high speed operation and capable of maintaining the accuracy of operation essential in hemstitching machines producing acceptable work.

For certain classes of work it is essential that the extent of vibration of one needle be greater than that of the other needle and it has heretofore been a common practice in 15 two-needle hemstitching machines to vibrate the needles by means of separate pitmen each adjustably connected with a cam-actuated segment, whereby the extent of lateral vibration of each needle could be determined 20 independently of the extent of vibration of the other needle. To meet the modern demands of high speed operation of machines, the present invention aims to provide a mechanism whereby the needles are both vibrated 25 by means of a single reciprocating pitman and whereby the extent of vibration of either needle with respect to that of the other needle may be readily changed with a minimum of correction for the inner positions of the 30 needles.

To this end, the reciprocating pitman is suitably connected with one arm of a bell-crank lever, fulcrumed upon the machine frame and of which the other arm is connected by separate links with actuating arms each secured upon a rock-shaft for adjustment transversely of the axis of the rock-shaft. The rock-shafts are journaled in the machine frame and each carries a crank- 40 arm which is clamped upon its rock-shaft to permit of adjustment of each crank-arm about the longitudinal axis of its rock-shaft. These crank-arms carry swivel-joints which as usual are slidily entered by needle 45 guide-rods fulcrumed upon a supporting plate at the lower end of the needle-bar and carrying the needles. The line of adjustment of each of the rock-shaft actuating arms closely approaches the arc of movement 50 of the point of pivotal connection of each actuating-arm with its operating link and therefore only a slight correction is required of the needle-position following upon adjustment of an actuating arm. This correction

may be readily obtained by reason of the 55 adjustable mountings of the crank-arms upon the rock-shafts.

In the accompanying drawings, Fig. 1 is a rear side elevation of a hemstitching machine containing the present improved needle-actuating mechanism. Fig. 2 is a front end elevation, partly in section, of the head of the machine bracket-arm. Fig. 3 is a front side elevation of the bracket-arm head. Fig. 4 comprises detail perspective views of 60 one of the needle-vibrating rock-shafts and its actuating arm.

The hemstitching machine illustrated in the drawings has the usual framework including the cloth-plate 1 from which rises the 70 hollow standard 2 of the overhanging bracket-arm 3 terminating in the head 4. Journaled in suitable bearings provided in the overhanging bracket-arm is the rotary main-shaft 5 carrying at one end the belt-pulley 6 75 and at its opposite end the crank-disk 7, connected in the usual manner by means of a link 8 with the needle-bar 9 journaled for vertical reciprocation in bearings provided in the head 4. The needle-bar 9 carries at 80 its lower end a supporting plate 10 pivotally sustaining a pair of needle-carriers 11 and 12. The needle-carrier 11 comprises an apertured sleeve 13 supported for oscillation upon a shouldered pivot-bolt 14, passing 85 through an elongated aperture 15 provided in the plate 10 and secured upon said plate by means of a nut 16 and washer 17. As will be evident, this construction provides for a lateral adjustment of the pivot-axis of 90 the needle-carrier upon the plate 10. Depending from the needle-carrier sleeve 13 is a clamp 18 for the shank of a needle 19 secured therein by means of a clamp-screw 20. Another clamp 21 integrally rising from the 95 sleeve 13 is provided with an aperture receiving the lower end of a substantially vertically disposed guide-rod 23, secured in said clamp 21 by means of a screw 24. Needle-carrier 12 is similar to the described carrier 100 11 in construction and in its pivotal support. Clamped to the needle-carrier 12 is a needle 25 and a substantially vertically disposed guide-rod 26, the supporting means for the needles and the guide-rods being evidently 105 such as to cause them to partake of the vertical reciprocations of the needle-bar.

The guide-rod 23 slidily enters a trans-

versely apertured swivel-pin 27 mounted within a lateral boss 28 on the free end of a crank-arm 29, disposed at the front of the bracket-arm head 4 and clamped upon a rock-shaft 30. The rock-shaft 30 has a substantially horizontal journal in a bushing 31 fixed in a suitable aperture provided in said head 4, said rock-shaft projecting beyond the rear face of the bracket-arm head. The rearwardly projecting end of the rock-shaft 30 has an enlarged portion or head 32 provided with a guide-rib 33, extending transversely of the axis of the rock-shaft and varying only slightly from a horizontal position during the operation of the machine. Adjustably seated upon the guide-rib 33 is a guideway 34 formed by grooving the inner face of an actuating arm 35, the base of the guideway 34 being provided with a slot 36 elongated in the direction of the length of the guideway. The head 32 of the rock-shaft is provided with an axially extending aperture 37 threaded to receive a securing screw 38 passing through the slot 36 and it is therefore evident that the crank-arm 29, rock-shaft 30 and actuating arm 35 constitute in effect a bell-crank lever having a substantial journal in the machine frame. The guide-rod 26 is similarly connected with a swivel-pin 39 within the boss 40 on a crank-arm 41 clamped to a rock-shaft 42 journaled in the head 4. Adjustably secured upon the rearward end of the rock-shaft 42, in a manner similar to the securing means for the actuating arm 35, is an actuating arm 43.

The actuating arms 35 and 43 are substantially horizontal, their free ends being directed toward each other and carrying pivot-pins 44 and 45 separately connected by equal length links 46 and 47 with an arm 48 of an elbow lever fulcrumed upon a pivot-pin 49 suitably fixed in the head 4. The links 46 and 47 have a coaxial pivotal connection with lateral projections 50 on the arm 48 of the elbow-lever, the other arm 51 thereof having an adjustable pivotal-connection with one end of a pitman 52 of which the opposite end has a similar connection with a slide-block 53. The slide-block 53 is secured for adjustment lengthwise of the channeled face of a vibratory arm 54 fulcrumed upon a shaft 55 journaled in the standard 2, said arm 54 being suitably vibrated by means of a grooved cam 56 rotated once for every three rotations of the main-shaft 5 through intermeshing gears 57 and 58.

Any suitable mechanism complementary to the needles in the formation of lock-stitches may be employed and the present disclosure is therefore confined to the needle-actuating mechanism described.

It will be apparent from the foregoing description that the extent of lateral vibration of either of the needles may be readily

varied by adjustment of either of the actuating arms 35 and 43 transversely of the axes of their respective rock-shafts and that the inner positions of the needles may be accurately determined by adjustment of the crank-arms 29 and 41 about their rock-shaft axes, thereby compensating for any slight rocking movements of the shafts 30 and 42 occasioned by adjustment of the arms 35 and 43. 75

Having thus set forth the nature of the invention, what we claim herein is:

1. A needle-actuating mechanism for hemstitching machines, comprising a reciprocatory needle-bar, a needle-carrier having a needle guide-rod pivotally supported upon said needle-bar, a bell-crank lever operatively connected with said guide-rod, means permitting adjustment of one of the arms of said bell-crank lever transversely of the axis of said lever and of the other arm of said lever about the axis thereof, and means for rocking said lever to impart vibratory movements to said needle guide-rod. 85

2. In a hemstitch sewing-machine having a cloth-plate and an overhanging bracket-arm, a needle-actuating mechanism comprising a reciprocatory needle-bar, a needle-carrier having a needle guide-rod pivotally supported upon said needle-bar, a rock-shaft 95 journaled in said bracket-arm, a crank-arm secured upon said rock-shaft for adjustment about the axis of said shaft, an actuating arm secured upon said rock-shaft for adjustment transversely of the axis of said 100 shaft, an operative connection between said crank-arm and the needle guide-rod, and means for operating said actuating arm to thereby vibrate the needle guide-rod. 105

3. Needle actuating mechanism for two-needle hemstitching machines, comprising a reciprocatory needle-bar, a pair of needle-carriers having needle guide-rods pivotally supported upon said needle-bar, a pair of crank-arms operatively connected with said 110 guide-rods permitting endwise movements thereof and adapted to impart sidewise movements thereto, a pair of rock-shafts carrying said crank-arms, a reciprocatory pitman, and operative connections for imparting rocking movements to both of said rock-shafts from said pitman including means for varying the throw of one rock-shaft with respect to the throw of the other. 115

4. Needle actuating mechanism for two-needle hemstitching machines, comprising a pair of reciprocating needles, means for reciprocating said needles, a reciprocatory pitman, and operative connections for laterally vibrating both of said needles from said pitman, including means for varying the lateral throw of one needle with respect to the lateral throw of the other. 125

5. Needle actuating mechanism for two- 130

needle hemstitching machines, comprising a pair of reciprocating needles, means for reciprocating said needles, a reciprocating pitman, and operative connections for laterally vibrating both of said needles from said pitman, including means for varying the lateral throw of either needle with respect to the lateral throw of the other.

6. In a hemstitch sewing-machine having a cloth-plate and an overhanging bracket-arm, a needle-actuating mechanism comprising a reciprocating needle-bar, a pair of needle-carriers pivotally supported upon said needle-bar, a pair of rock-shafts journaled in said bracket-arm, operative connections between said rock-shafts and the needle-carriers for imparting vibratory movements to said carriers, and operating mechanism for said rock-shafts including actuating arms secured upon said rock-shafts for adjustment transversely of the axes of said rock-shafts to thereby vary the throw of

either of said rock-shafts with respect to that of the other rock-shaft.

7. In a hemstitch sewing-machine having a cloth-plate and an overhanging bracket-arm, a needle-actuating mechanism comprising a reciprocating needle-bar, a needle-carrier pivotally supported upon said needle-bar, a rock-shaft journaled in said bracket-arm, operative connections between said rock-shaft and the needle-carrier for imparting vibratory movements to said carrier, an actuating lever fulcrumed upon the free end of said bracket-arm, means for actuating said lever, and operative connections between said lever and said rock-shaft including means for adjusting the extent of rocking movement of said shaft with respect to the extent of movement of said lever.

In testimony whereof, we have signed our names to this specification.

GEORGE M. EAMES.
JOHN C. RINGE.
